UNITED STATES PATENT OFFICE

156,216

DESIGN FOR A GLASS WASHER

Thomas H. Corbett, Chicago, Ill.

Application May 17, 1948, Serial No. 146,422

Term of patent 14 years

(Cl. D49—1)

To all whom it may concern:

Be it known that I, Thomas H. Corbett, a citizen of the United States, residing at Chicago, in the county of Cook and State of Illinois, have invented a new, original, and ornamental Design for a Glass Washer, of which the following is a specification, reference being made to the accompanying drawing, forming a part thereof.

The drawing is a front perspective view of a glass washer, showing my new design.

The side not shown is substantially the same as the one shown; and, the back is substantially plain.

I claim:

The ornamental design for a glass washer substantially as shown and described.

THOMAS H. CORBETT.
